[57] CLAIM

The ornamental design for a rotary dial day/night window clock, as shown and described.

DESCRIPTION

FIG. 1 is a front elevational view of a rotary dial day/night window clock showing my new design with the dial in the full day orientation;

FIG. 2 is a right side elevational view thereof, the left side being a mirror image thereof;

FIG. 3 is a rear elevational view thereof;

FIG. 4 is a top plan view thereof, the bottom plan view being a mirror image thereof; and,

FIG. 5 is a front elevational view thereof, showing the dial in the full night orientation.

FIG. 1

FIG. 2

FIG. 3

FIG. 4

FIG. 5
